UNITED STATES PATENT OFFICE.

JOHN B. HOWER AND JOSEPH V. ZELLER, OF AKRON, OHIO, ASSIGNEES TO THE AKRON-SELLER COMPANY, OF AKRON, OHIO, A CORPORATION OF OHIO.

LIQUID GAUGE.

Application filed March 5, 1923. Serial No. 622,736.

The present improvements, relating, as indicated, to liquid level gauges are directed more particularly to an improved and simplified gauge of the tube type which may be manufactured at an extremely low cost. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a longitudinal vertical section through our improved gauge; Fig. 2 is a plan view of the head which is inserted in the tank to support the gauge; Fig. 3 is a view in perspective of the dial; Fig. 4 is a similar view of the glass supporting ring; Fig. 5 is a similar view of the float; Fig. 6 is a section on the line 6—6, in Fig. 1; Fig. 7 is a bottom plan view of the tube and strip guide; Fig. 8 is a view in perspective of the strip guide; and Fig. 9 is a perspective view of the dial supporting plate in the head of the gauge.

In Fig. 1 there is shown a tank 1, which is provided with a suitable opening, in which is mounted an annular member 2 provided with a flange 3 resting upon the upper side of the tank 1, and provided with internal threading. Mounted in this head 2 is a second tubular flanged member or head 4 provided with projections 5 for convenient assembly into the head. This member 4 is provided with an inwardly directed flange 6, in which is formed a square opening 7. The flange 7 of this member 4 is also provided with two diametrically opposed holes 8. Mounted on the flange 7 is a dial plate 9, which is graduated as shown in Fig. 3, and which is provided with two diametrically opposed recesses 10, which are adapted to register over the holes 8 in the flange 7.

Mounted loosely on top of the dial 9 is a supporting or spacing ring 50, and supported on the upper edge of this ring is a flanged annular member 11 provided with an outwardly directed flange 12 resting on the ring 50, and an inwardly directed flange

13. Upon its inwardly directed flange is supported a transparent disk 14 of glass which is held in position by means of a flanged plate 15. This latter member is flared outwardly at its upper edge to fit over the curved corner or edge of the member 4 and is provided with an inwardly directed flange 16 adapted to rest upon the glass 14. Pins 17 are passed through holes in the plate 15 and these pins also pass through the recesses 10 in the dial plate, and the holes 8 in the plate 4, and are then upset at 18 on the bottom side of the plate 4 to securely hold the various parts in the head of the gauge in their relative positions. By the arrangement described the entire gauge head assembly can be made in small parts, which are cheap to manufacture, and which may be then assembled and locked by means of two pins or rivets.

The various parts employed in the head of the gauge may be cheaply manufactured either by die casting or by stamping, while when once assembled all of the parts are maintained in secure and tight engagement which prevents any rattling between these various parts and any leakage of liquid between the dial plate and the plate 20.

Rotatably mounted in a central opening in the dial plate is a shaft 25, on the upper end of which is carried an indicating hand 26, while from a point below the dial plate there extends a flat spiral strip 27. This strip extends the entire length of a square tube 28, which is soldered at its upper ends between the edges of the flange 7 and a stamped plate 40, (see Fig. 9). The lower end of the tube 28 is provided with a guide 29, the construction of which is shown in Fig. 8. This guide is provided with a central opening 30, in which is received the lower end of the strip 27.

Mounted in the tube 28 is a float 31 of buoyant material which is provided, on at least one horizontal surface, with a metal plate 32 which has a narrow rectangular opening 33 fitting snugly about the flat strip 27.

The operation of this gauge is as follows:—The liquid in the tank enters the tube through the opening in and around the plate 29 and lifts the float to the level of the liquid in the tank. The float is of the same form as the tube and cannot turn in the tube

so that the rising of the float turns the strip 27 and with it the indicating hand 26 and the latter is swept across the dial plate 9 and indicates the level of liquid in the tank.

5 Other modes of applying the principle of the invention may be employed instead of the one explained, change being made as regards the mechanism herein disclosed, provided the means stated by any of the following claims or the equivalent of such stated means be employed.

10 We therefore particularly point out and distinctly claim as our invention:—

15 1. In a liquid level gauge, the combination of a tubular head provided with an inwardly directed flange, said head being adapted to be mounted in an opening in the wall of a liquid reservoir, a dial plate loosely mounted on said flange, a tubular spacing ring on said 20 dial plate, said ring being spaced from the inner wall of said head, an annular member mounted on said ring, said member having an inwardly directed flange, a transparent disc mounted on said flange, and means engaging said dial plate and said head, said means being adapted to lock said dial plate,

spacing ring, annular member, and disc in tight relation.

2. In a liquid level gauge, the combination of a tubular head provided with an inwardly directed flange, said head being adapted to be mounted in an opening in the wall of a liquid reservoir, a dial plate loosely mounted on said flange, a tubular spacing ring on said dial plate, said ring being spaced from the inner wall of said head, an annular member mounted on said ring, said member having an inwardly directed flange, a transparent disc mounted on said flange, means engaging said dial and said head, said means including a flanged plate resting upon the upper edge of said head and bearing upon said disc, and means disposed between said spacing ring and said head, said means being adapted to fasten said flanged plate in place, locking 45 said disc, spacing ring, annular member and dial against relative movement.

Signed by us this 19th day of February, 1923.

JOHN B. HOWER.
JOSEPH V. ZELLER.
